UNITED STATES PATENT OFFICE.

DAVID C. KLAUSMEYER, OF CINCINNATI, OHIO, ASSIGNOR TO THE CINCINNATI BICKFORD TOOL COMPANY, OF CINCINNATI, OHIO, A CORPORATION OF OHIO.

CAM-CONTROLLED TWENTY-FOUR-SPEED MECHANISM.

Application filed May 5, 1925. Serial No. 28,214.

This invention relates to machine-tools and it deals more particularly with improved means for giving to a suitably journaled shaft, rotation at any one of a considerable number of speeds from a single speed in a prime mover. The invention may be utilized for any one of many purposes in connection with machine tools, such for example, as for rotating the spindle of a drilling and tapping machine or for actuating the spindle translating mechanism thereof. For convenience, it will be described in connection with the last-named mechanism but it is to be understood that this is merely one embodiment of the invention and that the invention also contemplates all of the various other uses for which a mechanism of this nature is adaptable.

The tool spindle of drilling and tapping machines is adapted to carry drills and taps of various diameters and inasmuch as each of these tools requires a different speed of rotation and also a different rate of feed, for maximum efficiency, it is essential that means be provided for producing these varying speeds. Also it is desirable that the means for producing these various speeds be as simple as possible in construction and that the means for controlling the speeds produced be readily accessible to the operator and adapted readily to be manipulated without confusion to produce any desired speed.

This invention therefore has for an object to render available a multiple speed mechanism capable of being manipulated to produce any available speed by a single lever readily accessible to the operator and adapted to be shifted in accordance with indicia provided by an index plate adjacent the lever.

Another object of the invention is to provide a multiple speed mechanism comprising a plurality of shiftable and non-shiftable gear units and to provide an improved cam controlled shifting mechanism for certain of the shiftable gear-units.

Another object is to provide an improved index plate by the aid of which the operator readily may be advised as to the extent of axial feed of the tool per revolution of the tool spindle in all of the various operative positions of the lever.

Still another object of the invention is to provide a feed index plate by the aid of

which the operator may, with great facility and without calculation, readily set the lever to the proper position to effect the necessary gear setting so to coordinate the speed of rotation of the spindle with its axial feed as to adapt the machine to tap any one of certain standard threads.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a sectional development of the improved multiple speed mechanism as utilized to actuate a spindle feed mechanism. Fig. 2 is a plan of the mechanism illustrated in Fig. 1 with the parts in their normal operative positions. Fig. 3 is a development of the gear shifting cams, the intermediate cam being shown as shifted approximately 180 degrees to bring the starting points of all of the cams in the same vertical line more clearly to illustrate the functioning of the cams. Fig. 4 is a detail showing means for throwing out a manual feed when the power means is rendered effective to translate the spindle. Fig. 5 is a face view of the feed-plate used in connection with the feed-controlling lever to indicate the feed in thousandths of an inch per rotation of the prime mover. Fig. 6 is a diagrammatic view illustrating the flow of motion through the change gears, selectively to produce any one of twenty-four speeds.

Referring more particularly to the drawings, the invention is illustrated as embodied in a spindle feed mechanism for drilling machines, by means of which the spindle may be fed lengthwise at any one of a plurality of speeds to cause the tool carried thereby to enter and emerge from the work; the rate of feed being determined by the size and type of tool being used and the nature of the work being operated on. In the drawings S designates the spindle formed in its lower end with a socket x adapted to receive any one of the tools commonly used in this type

of machine tool. Any suitable means may be employed to rotate the spindle and inasmuch as the spindle rotating means forms no part of this invention illustration and description thereof is deemed unnecessary.

During the rotation of the spindle, it is necessary that the spindle be moved lengthwise for purposes hereinbefore described. This may be effected by having the spindle 10 rotatably but non-translatably journaled in a sleeve 1 provided with a rack 2 with which meshes an actuating pinion 3 secured upon a shaft 4 journaled transversely to the spindle. A worm-wheel 5, also secured upon the shaft 15 4, is driven by a worm 6 fixed upon a power delivery shaft 7 adapted selectively to be rotated at any one of a plurality of speeds by means later to be described.

Power to actuate the spindle feed mechanism may be provided by any suitable prime mover, such for example, as a gear P secured upon a suitable spindle driving sleeve D . Power from the prime mover flows to the power delivery shaft through three separate speed change mechanisms A, B and C affording respectively two, four and three speed changes which together render available twenty-four speeds in the power delivery shaft. The speed change device A 20 includes a gear-unit 8 splined upon a shaft 9 journaled parallel with the spindle and adapted to be driven from the gear P through a gear 10 fixed to said shaft, and permanently in mesh with said gear P . The gear-unit 8 provides gears a and b adapted selectively to be meshed with gears c and d , respectively, provided by a gear unit 11 rotatably journaled on a shaft 12 parallel with the shaft 9.

The speed change device B comprises gears c , e , f and g provided by the gear-unit 11 and gears $h-i$, and $j-k$ provided by gear units 13 and 14 splined upon a sleeve 15 rotatably journaled on the power delivery shaft 7. The sleeve 15 carries a gear l constituting the initial gear of the speed change device C. This gear is maintained permanently in mesh with a gear m provided by a gear-unit 16, rotatably journaled 40 on the shaft 12, and is also adapted to be engaged by a clutch element n provided by a shiftable gear-unit 17 splined to the power delivery shaft 7. The gear-unit 16 also provides a gear o adapted to be meshed with a gear p forming a part of the gear-unit 17. A gear q is rotatably journaled on the shaft 12 and is adapted to be meshed with a gear r provided by the gear unit 17. The gear q is, in effect, a part of the gear unit 16 and may be made integral therewith, but, for convenience of manufacture and assembling, it preferably is made as a separate part and connected therewith by means of clutch elements s and t .

Means, later to be described, is provided

for shifting the gear-units 8, 13, 14 and 17 selectively to produce any one of twenty-four speeds in the power delivery shaft from a single speed in the prime mover. The scheme of the transmission and the various gear settings to produce any desired speed in the power delivery shaft will be clearly understood by referring to Fig. 6. The single speed in the shaft 9 passes through the speed change device A either through gears a and c or b and d thus delivering two speeds to the device B. Likewise these speeds are multiplied by four in the device B by causing the power selectively to flow through gears $c-h$, $e-i$, $f-j$ or $g-k$, thus delivering eight speeds to the speed change device C. These eight speeds are further multiplied into twenty-four speeds by the speed-change device C, by selectively meshing the gears thereof so that power may flow through any one of the three courses now to be described. By shifting the gear-unit 17 upwardly so as to engage it directly with the sleeve 15 power will be caused to flow through gear l and clutch n carried by the gear unit 17 splined to the power delivery shaft thus delivering to the shaft 7 the eight speeds produced by the devices A and B. Eight additional speeds may be obtained through gears l , m , o and p . Still another eight speeds are available through gears l , m , q , and r .

As hereinbefore stated this invention provides a single shifting device for all of the gear-units 8, 13, 14 and 17. This shifting device comprises a lever 18 fulcrumed at 19 in a yoke 20 projecting laterally from a sleeve 21 rotatably journaled in a stationary framework 22. Splined within the sleeve 21 is a shaft 23 formed with a rack 24 maintained permanently in mesh with a segment 25 on the lever 18. Fixed upon the upper end of the shaft 23 is a gear shifter 26, preferably in the form of a semi-circular disk which engages an annular groove 27 in the gear unit 17. Thus it will be seen that vertical movement of the lever 18 about its fulcrum 19 will, through the segment 25 and rack 24, cause the shaft 23 to be shifted axially and the shifter 26 will move the gear unit lengthwise of the power delivery shaft 7 selectively to engage the clutch n and the gear l , the gears o and p or the gears q and r . Due to the construction of the shifter 26, the shaft 23 may be given a half rotation, for purposes later to be explained, without disturbing the operative connection between the shifter 26 and the gear-unit 17.

The gear-unit 8 is engaged by a shifter 28 translatably mounted on a shaft 29 carried by the stationary frame. The gear-units 13 and 14 are engaged by shifters 30 and 31 respectively likewise translatably mounted on a shaft 32 held in the stationary frame. The shifters 28, 30 and 31 carry studs or

rollers 28^a, 30^a and 31^a, respectively, which track cam grooves 33, 34 and 35 formed in a rotatable cam cylinder 36. In Fig. 1 the cam cylinder is shown in full lines at the right of the figure and in dotted lines at the left thereof more clearly to show the connection between the shifter 28 and its actuating cam groove 33. It will readily be perceived that rotation of the cam cylinder 36 will through the cam grooves, cause the shifters 28, 30 and 31 to be translated thereby shifting the gear units so to mesh the gears as to produce any one of the available speeds. The shifters are preferably formed 10 with bifurcated ends 28^b, 30^b, and 31^b respectively which embrace the cam cylinder and prevent rotation of the shifters about their supporting shafts. By guiding the shifters adjacent the point where the power is applied and close to the supporting shafts, the shifters are also prevented from binding on their supports and are therefore maintained freely translatable thereon.

To effect rotation of the cam cylinder, it 25 may be secured to a shaft 37 rotatably journaled in the frame 22. This shaft also carries an elongated gear 38 held to rotate synchronously with the cam cylinder 36. A gear segment 39, fixed to the shaft 23 and 30 preferably formed integral with the gear shifter 26, meshes with the gear 38 and acts, upon rotation of the shaft 23 to rotate the said gear and the cam cylinder. Thus it will be seen that by moving the lever 18 in a 35 horizontal plane, about the axis of the shaft 23, it will, through the yoke 20 and sleeve 21, cause rotation of the shaft 23, segment 39, gear 38 and cam cylinder 36 to shift the gear units 8, 13 and 14 to produce eight 40 speeds in the sleeve 15. The gear unit 17 may be shifted vertically to multiply by three the eight speeds delivered thereto, by vertical movement of the lever 18 as hereinbefore described. It is to be understood that 45 the lever 18 may be moved horizontally to eight operative positions to effect the eight speeds provided in the speed change devices A and B, and to three vertical positions to effect the three speeds provided in the device C. As shown more clearly in Fig. 2, 50 the pitch radius of the gear segment 39 is substantially greater than the pitch radius of the gear 38 and therefore a one-half rotation of the segment will give the gear and the cam cylinder more than one complete 55 rotation. The cam grooves 34 and 35 are continuous about the periphery of the cam cylinder but the cam groove 33 is non-continuous and extends once and seven-tenths 60 about the cam cylinder.

Referring to Fig. 2, it will be seen that the pin 28^a enters its cam groove 33 at the diametrically opposite side of the cam cylinder from the pin 30^a and therefore it is to 65 be understood that the starting point of the

cam groove 33 is 180 degrees from the starting point of the grooves 34 and 35. For the purpose of more clearly setting forth the co-ordination and functioning of the cams, in Fig. 3 the cam 33 is shown as shifted 180 degrees about the cam cylinder to bring the starting points of all of the cams on the same vertical line.

Referring now to Fig. 3 in which the entire cam cylinder is shown developed and for convenience of description is shown as divided into ten equal divisions, the starting points of the cams, 33, 34 and 35 are indicated by 33^s, 34^s and 35^s respectively.

The lever 18 is adapted to be moved horizontally about 180 degrees and this motion, through the segment 39 and gear 38, gives to the cam cylinder one and seven-tenths rotations. Now considering that the lever is at one of its extreme horizontal positions, 80 that the pins 28^a, 30^a and 31^a are in their starting positions 33^s, 34^s and 35^s in the cams 33, 34 and 35, and the lever subsequently is swung about the axis of the shaft 23 in the direction to rotate the cam cylinder in 90 the direction indicated by the arrow in Fig. 3, the action of the cams to shift the gears of the devices A and B will be as follows:— The pin 28^a is now in the lowermost effective run 33^a of the cam 33 and therefore the gear *b* is in engagement with the gear *d*, (which engagement it maintains for eight-tenths of a rotation of the cam cylinder, or until the pin 28^a reaches the point 33^b of the cam 33). The pins 30^a and 31^a are in 95 the neutral portions of the cam grooves 34 and 35 respectively. A one-tenth rotation of the cam cylinder causes the cam groove 35 to shift the stud 31^a to the position 35^b which causes the gear unit 14 to be shifted 100 downwardly to mesh the gears *g* and *h* thereby effecting a drive through the speed change devices A and B through gears *b*—*d*—*g*—*k* (see Fig. 6). A further two-tenths rotation of the cam cylinder will then cause the stud 105 31^a to be shifted through the neutral position 35^c to the effective point 35^d which causes the gear unit 14 to be shifted upwardly and effecting a drive through *b*—*d*—*f*—*j*. It is to be noted that during this 110 movement the stud 28^a continues to track the lower effective run 33^a and the stud 30^a is tracking a neutral portion of the cam groove 34. A further two-tenths rotation of the cam cylinder shifts the stud 31^a through 115 the position 35^e (which causes the gear unit 14 to be shifted to its neutral position) and the stud 30^a is moved to the position 34^b in the cam groove 34 thereby shifting the gear-unit 13 downwardly and effecting a drive 120 through the gears *b*—*d*—*e*—*i*. Another two-tenths rotation of the cam-cylinder shifts the stud 30^a through the neutral position 34^c in the cam groove 34 to the position 34^d, thereby shifting the gear unit 13 upwardly, 125

130

engaging the gears *c*—*h* and effecting a drive through gears *b*—*d*—*c*—*h*. A further three-tenths rotation of the cam shifts the stud 34^a through the neutral portion 34^c of the cam 34 and shifts the stud 28^a from the effective run 33^a, through the neutral point 33^c, and into the upper effective run 33^d, thereby shifting the gear unit 13 to its neutral position and shifting the gear unit 10 8 upwardly to mesh the gears *a* and *c*.

It is to be observed that the cam cylinder has now received one complete rotation and the cam grooves 34 and 35 have each performed its complete operation, that is successively to shift the gear units 13 and 14, respectively, to their two operative positions, while the portion 33^a of the cam groove 33 maintained the gears *b* and *d* in mesh, thereby combining the four speed changes afforded by the speed device B with the gears *b* and *d* of the device A. The stud 28^a also has been shifted to the upper effective run 33^d and in a further seven-tenths rotation of the cam cylinder the cam grooves 35 and 34 20 will again shift the studs 31^a and 30^a respectively, as previously described, again to cause gear units 14 and 13 each again to be shifted to its two effective positions; thus during this last seventh-tenths rotation the 25 gears *g*—*k*, *f*—*j*, *e*—*i*, and *c*—*h* are successively combined with the gears *a* and *c* and four more speeds are provided. This last seven-tenths rotation of the cam cylinder brings the studs 30^a and 31^a to the points 30 34^a and 35^a in the cam grooves 34 and 35, respectively, and the stud 28^a contacts with the closed end 33^e of the cam groove 33 thus preventing further rotation of the cam cylinder and thereby preventing further movement of the lever 18.

Each of the eight speeds provided by the speed change devices A and B may be multiplied by three in the device C by moving the lever in a vertical plane thus producing 45 the twenty-four speeds hereinbefore described.

The gear-shifters 26, 28, 30 and 31 are provided with spring detents 26^a, 28^a, 30^a and 31^a, respectively, which engage suitable 50 notches to prevent accidental movement of the shifters. As shown in Fig. 1 the detent 26^a is adapted to engage any one of four detent notches 26^a, 26^b, 26^c or 26^d. The notches 26^a, 26^b and 26^c correspond to lower, 55 intermediate and upper operative positions respectively of the gear-unit 17 and the notch 26^d corresponds to the neutral position of said gear unit 17, that is with the gears *p* and *r* intermediate the gears *o* and *q*.

In addition to the hereinbefore described 60 power drive for the worm 6, means also is provided whereby the worm may be rotated manually and this manual drive is so coordinated with the power drive that they 65 both may not be effective at the same time.

This is accomplished by providing automatically acting means to hold the manual means out of action whenever the power feed is effective and to connect the manual means when the power feed is thrown out. To that end, a clutch element 40 is fixed to the shaft 7, and this clutch element is adapted, at certain times, to be engaged by a similar clutch element 41. This latter clutch element is carried by a shaft 42 which is translatably mounted in the hub 43 of a hand wheel 44, rotatably journaled in a bearing 45 with its axis coincident with the axis of the shaft 7. A spring 46 interposed between the shaft 42 and a screw 47 threaded into the hand-wheel normally tends to move the shaft 42 axially to engage the clutch members 40 and 41. The clutch member 41 and shaft 42 may be shifted against the action of the spring 46 by means of a bell-crank lever 48 fulcrumed at 49. One arm of the lever 48 carries a shoe 50 which tracks a groove 51 in the clutch element 41 and the other arm carries a contact point 52 which bears against the periphery of the shaft 23 under the action of the spring 46. The shaft 23 is formed with an annular notch 53 into which the point 52 drops when the lever 18 and the shaft 23 are in their neutral positions. The notch 53 is formed with upper 95 and lower inclined walls 53^a and 53^b which, when the shaft 23 is moved axially from its neutral point, act as cams on the point 52, and cause the lever 48 to be swung about its fulcrum to disengage the clutch elements 40 and 41. From the foregoing it will be perceived that either the manual drive or the power drive may be rendered effective but that they both may not be effective simultaneously.

Another important feature of this invention resides in the employment of the specially designed index plate 60, shown in Fig. 5, in combination with the single gear shifting lever 18. This index plate is supported by 110 a stationary part of the tool-head, concentric with the shaft 23, and is divided into three horizontal rows *x*, *y* and *z* of indicia corresponding to the three vertical positions 18^x, 18^y and 18^z of the lever 18 (see Fig. 1). 115 Each of these three rows is divided into eight sub-divisions corresponding to the eight horizontal positions of the lever 18 thus twenty-four sub-divisions are provided each of which carries indicia indicating one 120 of the feeds effected by a predetermined setting of the lever 18. An indicator, preferably in the form of a pointer 61, is carried by the lever and has its free end movable both vertically and horizontally across the face of the index plate. The indicia provided by each of the subdivisions preferably indicate the feed in thousandths of an inch per rotation of the spindle. This 125 is feasible because of the fact that the prime 130

mover for the feed is operatively connected with the spindle and therefore the speed of rotation of the spindle and the feed therefor are coordinated and by setting the pointer 61 to any one of the subdivisions on the index plate the gears of the speed change devices A, B and C will be so meshed as to produce the feed indicated in said subdivision. The index plate also is provided with 5 a horizontal blank *w*, between the rows *x* and *y* corresponding to the neutral position 18^w of the lever 18. When the tip of the pointer 61 is brought adjacent this blank the detent 26^a engages the detent notch 26^a 10 and holds the gear-unit 17 in its neutral position with the gears *p* and *r* thereof intermediate the gears *o* and *q* of the gear unit 16. In this position the power feed is rendered ineffective and the manual feed is 15 thrown in as hereinbefore described.

As is well understood, these machine tools are also used for tapping and therefore in order to tap a hole with a standard thread, it is necessary that only a certain predetermined feed be employed. For example, the standard screw thread for a one-inch hole is eight threads per inch, therefore if it is desired to tap such a hole it is necessary that the tap be advanced one-eighth of an inch 20 (or .125 inch) for each rotation thereof. In that case, the lever 18 would be shifted to bring the tip of the pointer to the subdivision *z'* which is marked 125F indicating a feed of .125 inch per rotation of the tool 25 spindle.

To enable the operator readily and without calculation to shift the gears to produce any available standard tap lead, those subdivisions which produce spindle feeds, corresponding to the various standard tap 30 leads, also contain indicia to indicate that fact. For instance, the subdivisions *z'* also contains the marking 8T which indicates that when the pointer is brought to that subdivision the gears will be so meshed as to 35 tap eight threads per inch.

Still further to assist the operator in selecting the settings which produce the standard tap leads the subdivisions which indicate such settings are preferably of a color 40 in contrast with the color of the subdivisions which do not indicate a standard tap lead and which are used primarily for drilling feeds. For example, the subdivisions *z'*, *z²*, *z³*, *z⁴*, *z⁵*, *z⁶*, *y'* and the instruction subdivision *v* may have a back ground of black and the remainder of the subdivisions and the blank *w* may have a back ground of red, but any other contrasting colors may be 45 used. For convenience, the tap feed subdivisions are shown in black and the drill feed subdivisions are shown in white, but it is to be understood that these colors are only representative.

50 From the foregoing, it will be perceived

that this invention provides a very simple and efficient means in the form of a single lever for shifting all four of the shiftable gear units. It will also be seen that by utilizing the cam grooves 34 and 35 twice, 55 the diameter of the cam cylinder may be made substantially smaller than if the usual practice was followed and each cam groove was used only once in a complete gear shifting cycle. This reduction in size and the 60 consequent compactness of parts secured thereby is of great importance inasmuch as much mechanism is embodied in these drill-heads and very little space is available. Furthermore, it will be perceived that the 65 new feed plate will greatly assist the operator in effecting the proper setting of the gears and fewer mistakes will be made than heretofore.

Without further analysis, the foregoing 70 will so fully reveal the gist of this invention that others can, by applying current knowledge, readily adapt it for various utilizations by retaining one or more of the features that, from the standpoint of the 75 prior art, fairly constitute essential characteristics of either the generic or specific aspects of this invention and, therefore, such adaptations should be, and are intended to be, comprehended within the meaning and 80 range of equivalency of the following claims.

Having thus revealed this invention, I claim as new and desire to secure the following combinations and elements, or equivalents thereof, by Letters Patent of the 85 United States:—

1. A multiple speed mechanism combining a prime-mover; a rotatable member; means operatively connecting said prime mover with said rotatable member, said means including a plurality of shiftable gears; means to shift said gears selectively to produce any one of a plurality of drives between said prime mover and said member, said gear shifting means comprising a lever 90 movable in transverse planes; a rotatably and translatable mounted shaft; two operative connections between said lever and said shaft, whereby movement of said lever in one plane rotates said shaft and movement of said lever in another plane translates said shaft; a gear shifter secured to said shaft and adapted to shift one of said shiftable gears by the axial movement of said shaft; a rotatable cam operatively connected to actuate another of said gear shifters; and an operative connection between said shaft and said cam to cause said cam to be rotated by the rotary movement of said shaft.

2. In a multiple speed mechanism including a plurality of shiftable gears; a plurality of gear-shifters each operatively connected with one of said gears; a shaft upon which one of said gear-shifters is secured; means to move said shaft axially to cause 100

5 said last named gear-shifter to shift one of said gears; a rotatable cam operatively connected to actuate another of said gear-shifters; a gear rotatable with said cam; a gear- segment meshing with said gear and operatively connected with said shaft; and means to rotate said shaft to cause said segment to rotate said last named gear thereby to cause

10 3. In a multiple speed mechanism including a plurality of shiftable gear-units; a shaft adapted to be rotated and translated; a gear-shifter and a gear-segment secured to said shaft and movable axially and rotatively therewith; a gear-unit engaged by said gear-shifter and adapted to be actuated by the axial movement of said shaft; a gear meshing with said segment and adapted to be actuated by the rotative movement of said shaft and segment; a cam rotatable with said gear; a gear-shifter actuated by said cam and adapted to shift one of said gear units; and means to rotate and translate said shaft.

15

20

25 4. In a multiple speed mechanism including a plurality of shiftable gear-units; a shaft adapted to be rotated and translated; a gear-segment and a gear-shifter secured to said shaft and movable axially and rotatively therewith; a gear-unit engaged by said gear-shifter and adapted to be moved by the axial movement of said shaft; a gear meshing with said segment and adapted to be rotated by the rotative movement of said shaft; a gear-shifter engaging one of said shiftable gear-units and adapted to be actuated by the rotary movement of said gear; a rack on said shaft; a member mounted coaxial with said shaft and rotatable therewith; a lever fulcrumed on said member; a gear-segment provided by said lever and

adapted to mesh with said rack, said parts being so constructed and arranged that movement of said lever about its fulcrum shifts the shaft axially and movement of the lever about the axis of the shaft rotates said shaft. 45

5. A drilling and tapping machine combining, a rotatable and translatable spindle; spindle translating means comprising a prime mover, three serially arranged speed change devices connecting said prime mover with said spindle and affording respectively two, three and four speed changes to give to said spindle twenty-four feed rates from a single speed in said prime mover, each of said speed change devices including shiftable and non-shiftable gears; gear-shifters engaging said shiftable gears; a rotatable and translatable shaft connected with said gear shifters and adapted by rotation and translation to actuate all of said shifters; a single lever movable in one plane to three positions and in a plane transverse to the first mentioned plane to eight positions for each of the three first mentioned positions thereby to rotate and translate said shaft to effect all of said twenty-four feed changes; a pointer carried by said lever; and an index plate underlying said pointer and provided with three rows of indicia corresponding to the three positions of said lever in one plane, each of said rows comprising eight symbols corresponding to the eight positions of said lever in the other plane, each of said symbols cooperating with said pointer to indicate the spindle feed rate effected by movement of said lever and pointer to the indicated position.

In witness whereof, I have hereunto subscribed my name. 80
DAVID S. KLAUSMEYER
